UNITED STATES PATENT OFFICE.

CHARLES C. LOCKSTAEDT, OF CHICAGO, ILLINOIS.

SPLIT PULLEY.

SPECIFICATION forming part of Letters Patent No. 484,935, dated October 25, 1892.

Application filed February 16, 1892. Serial No. 421,772. (No model.)

To all whom it may concern:

Be it known that I, CHARLES C. LOCKSTAEDT, a subject of the Emperor of Germany, residing at Chicago, in the county of Cook 5 and State of Illinois, have invented certain new and useful Improvements in Split Pulleys; and I do hereby declare the following to be a full, clear, and exact description of the invention, such as will enable others skilled in the 10 art to which it appertains to make and use the same.

This invention relates to a novel construction in split pulleys, the objects being to provide a metallic pulley that can be easily applied and removed from the shaft, and to provide a metallic split pulley that is true and that can be made in an inexpensive manner.

The invention consists in the features of construction and combinations of parts herein- 20 after fully described and specifically claimed.

In the accompanying drawings, illustrating my invention, Figure 1 is a side elevation of a pulley constructed in accordance with my invention before the block is secured in place. 25 Fig. 2 is a similar view with the block in place. Fig. 3 is a sectional view on the line 3 3 of Fig. 2. Fig. 4 is a sectional view on the line 4 4 of Fig. 2. Fig. 5 is a side elevation of the pulley finished and secured to a 30 shaft. Fig. 6 is a detail side elevation of the block.

Referring to said drawings, A indicates as a whole the pulley, and B the block. The said pulley embraces a rim 1, a hub 2, single spokes 3, and double spokes 4 and 5, the latter being arranged diametrically opposite each other. The double spokes 4 are located parallel with each other and are joined to the hub at their inner ends and to the rim at their 40 outer ends. The said rim 1 is open or discontinued between the outer ends of the spokes 4 to form a recess or open slot 6 between the spokes 4, by means of which the pulley can be placed upon a shaft. The 45 spokes 4 are provided on their inner faces with the lateral flanges 7. The block B is adapted to enter the open slot 6 of the pulley and consists of a web 8, side flanges 9, the wide rim portion 10, and hub end 11.

50 In constructing said pulley the pulley proper is molded and the inner faces of the

flanges 7 are planed to receive the block B, the outer faces of the flanges 9 of which are also planed, so that said block fits nicely within the open slot 6. Two rabbets 12 are 55 also made in the rim of the pulley at the juncture of the same with the spokes 4, and these rabbets receive the lugs 13 on the outer end of the block B, said rabbets 12 and lugs 13 being planed to fit each other nicely. The 60 block is then fitted in place, with its flanges 9 fitting against the flanges 7 of the pulley and the lugs 13 within the rabbets 12. The flanges are then bolted together by bolts 14 in an obvious manner. The rim 1 and rim- 65 piece 10 are then trimmed down to make them perfectly true, and the hub 2 and hub- piece 11 of the block turned out to bring it to the right size, as shown in Fig. 5. The pulley is then ready for use and can be taken 70 apart and shipped. It is plainly obvious that when the pulley is to be applied to a shaft it can be easily slipped thereon and the block put in place and secured, which will make a firm and true pulley. It will be noted that if 75 there was a plurality of such pulleys upon a shaft then the double spokes 4 of such pulleys could be located on opposite sides there- of to balance each other; but to insure the 80 balancing of said shaft each pulley A is pref- erably provided opposite the double spokes 4 with the double spokes 5, before referred to. Near the outer end of said spokes 5 and ad- jacent the rim is located a weight 15. Said 85 double spokes 5 and weight 15 serve to coun- terbalance the double spokes 4 and block B. The weight 15 can, furthermore, be reduced by boring holes therein in an obvious manner, so that the two sides of the pulley will balance perfectly.

90 I claim as my invention—

1. A pulley having double-flanged spokes, an open slot between said spokes extending from the center to the rim, and a block embracing a web 8, side flanges 9, rim portion 95 10, and hub end 11, located within said slot and adapted to be secured therein by bolts passing through said flanges, substantially as described.

2. A pulley having double-flanged spokes, 100 an open slot between said spokes, extending from the center to the rim and having rab-

bets formed at the juncture of said spokes and rim, and a block embracing a web 8, side flanges 9, hub end 11, and rim portion 10, having lugs 13, located within said slot and adapted to be secured therein by bolts passing through said flanges, substantially as described.

In testimony whereof I affix my signature in presence of two witnesses.

CHARLES C. LOCKSTAEDT.
